Owen, Owen & Cawley

UNITED STATES PATENT OFFICE.

THOMAS J. KEHOE, OF TOLEDO, OHIO.

AUTOMOBILE-RADIATOR.

1,184,751.

Specification of Letters Patent.

Patented May 30, 1916.

Application filed February 26, 1915. Serial No. 10,835.

To all whom it may concern:

Be it known that I, THOMAS J. KEHOE, a citizen of the United States, and a resident of Toledo, in the county of Lucas and State of Ohio, have invented a certain new and useful Automobile-Radiator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to automobile radiators, and it has for its object to provide a radiator wherein the parts may be easily made and assembled. It also has for its object to so connect the parts of the radiator that they may be easily removed when repair thereof is necessary.

The radiators involving my invention are formed of a plurality of strips which are formed shallow trough shaped and which may be placed edge to edge, to produce water cells or conduits through which the water may be carried while it is being cooled by the air that passes between the cells. The strips instead of being placed edge to edge may be folded centrally and opposite edges brought into juxtaposition. They may then be sealed along the edges which are thus brought together. By my invention also is provided a spacing means which is formed in the strips so that the cells may be placed in parallel relation by merely bringing the cells together. This will permit ready assemblage of the parts and form passageways which will permit the air to freely pass between the cells. By my invention is also provided a means for spacing the edges of the cells and a means which produces local whirls of the air as it passes between the cells and also forms a radiating surface to dissipate the heat contained in the water which passes through the cells. The construction also is such that if one of the cells needs repair all that is necessary is to melt the solder along the points of contact or connection with the other parts of the radiator. Whereby the cells may be removed and the repairs may be made in the cell as may be deemed necessary. The cell may then be replaced and re-soldered in position in the radiator. Also, by my invention a ra-

diator is produced wherein the water cells are sealed and secured together by a very little solder, thereby greatly reducing the cost of production. In the radiators now known in the art, the overlapping parts take up the solder in great quantities by reason of the capillary action of the closely positioned strips, and consequently an enormous quantity of solder is used. In the preferred form of the construction involving my invention there are only two narrow edges which are placed side by side and which are dipped for purposes of sealing the cells so that the amount of solder is reduced to a minimum.

The invention may be contained in many forms of heaters, coolers and heat radiating devices usable for different purposes all of which come within the purview of my claims hereinafter appended. To show the practicability of my invention, I have selected one of such constructions as an example and shall describe it hereinafter. The construction selected is illustrated in the accompanying drawings.

In the drawings, Figure 1 illustrates a front view of the radiator. Fig. 2 illustrates a section of the upper compartment or chamber of the radiator. Fig. 3 illustrates a number of cells secured together. Fig. 4 is an end sectional view of the cluster shown in Fig. 3. Fig. 5 illustrates a spacing strip which is located between side edges of adjoining cells. Fig. 6 illustrates an end sectional view of the shallow trough shaped strips which may be united to form cells.

Fig. 1, is the framework of the radiator. It is provided with the usual upper compartment 2 and the lower compartment 3. The jackets of the engine are connected to the two compartments 2 and 3. The water being heated by the explosions in the cylinders of the engine passes from the jackets of the engine and enters the upper compartment 2, passes down through the water cells 4, while it is being cooled by the air passing between the cells, to the lower compartment and thence it passes to the jackets of the engine, the circulation being caused by the difference in the weight of the water in the two parts of the circuit by reason of the difference in the temperature, it being heated by the engine and cooled by the radiator in the manner well known in the art. The usual cap 5 is also provided for closing the

funnel or mouth piece 6 through which water or other suitable cooling medium may be poured into the radiator.

The water cells 4 are made of strips 10 sufficiently long to extend from the upper compartment 2 to the lower compartment 3. They are made shallow trough shaped and formed with flanges 11 and 12 along their side edges and flanges 13 along their end edges. The strips 10 may be placed side by side in the manner shown in Fig. 6 and so that the flanges 11, 12 are placed in close contact with each other to form the cells 4, or the strips 10 may be bent centrally as shown in Fig. 4 so as to bring opposite side flanges 11 and 12 into contact with each other to form the cells 4.

The walls of the cells have a spacing means formed therein. Raised portions 15 are formed in the stamping of the strips 10. The raised portions 15 may be made in any suitable shape, but they are preferably made frustumal whereby flat contact surfaces 16 are formed on each raised portion. The contact surfaces or raised portions of adjoining cells are placed in thrust relation to each other. The cells when bound together are thus held in spaced relation.

The edges of the cells formed by the flanges 11 and 12 are also held in spaced relation by a spacing means. In the form of the invention shown the edge spacing means consists of a plurality of transverse pieces 20 preferably made in the forms of tongues 20 extending from a strip 21. The tongues 20 are twisted so that the plane of each tongue extends at right angles to the plane of the strip 21 forming thereby a short twisted or screw shaped portion 22 at the point of connection between the tongue portions and the strip. The strips 21 are placed centrally with respect to the side edges of the cells and so that the tongues between the cells extend in parallel planes across the radiator. They are secured in this position when the radiator is dipped in the solder to seal the side edges of the cells 4. The slight twisted portion of the tongues operates to cause the air to be turned or whirled somewhat in its passage through the cells thereby bringing the air into contact with the walls of the cells. The flanges 13 which extend at right angles to the cells at the top thereof overlap. The overlapping flanges of adjoining cells are secured together by solder. The structure thus formed is secured in position in the radiator between the two cham-

bers 2 and 3. The air passing in between the cells as the water, which passes down through the cells and to the engine, cools it. 60

The construction selected and described may be greatly varied in the arrangement and manufacture of its parts and in the substitution of elements having equivalent functions and such modifications may be 65 used for many varied purposes and still contain the invention.

Having thus described my invention, what I claim as new and desire to secure by Letters Patent, is,—

1. A radiator having a plurality of vertical cells, the cells having flanges composed of edges of the sheet metal of the cells sealed together, and displaced from the planes of the side walls of the cells, strips 75 extending centrally with respect to the edges of the cells, the strips having tongues located in parallel planes extending at right angles to the strips, the tongues fitting the flanges of the cells, and the flanges and 80 tongues secured together by solder.

2. A radiator having a plurality of vertical cells, the cells having flanges composed of edges of the sheet metal of the cells sealed together, and displaced from the planes of the side walls of the cells, strips 85 extending centrally with respect to the edges of the cells, the strips having spirally twisted tongues located in parallel planes extending at right angles to the strips, the 90 tongues fitting the flanges of the cells, and the flanges and tongues secured together by solder.

3. A radiator having a plurality of vertical cells, the cells having flanges composed 95 of edges of the sheet metal of the cells sealed together, and displaced from the planes of the side walls of the cells, strips extending centrally with respect to the edges of the cells, the strips having spirally twisted 100 tongues located in parallel planes extending at right angles to the strips, the tongues fitting the flanges of the cells, the flanges and tongues secured together by solder, and the edges of the tongues between the spiral 105 portions having a length substantially the same as the width of the flanges of the cells.

In testimony whereof, I have hereunto signed my name to this specification in the presence of two subscribing witnesses.

THOMAS J. KEHOE.
